Primary Examiner — John A Voytek(74) *Attorney, Agent, or Firm* — Martensen IP; Michael C. Martensen(57) **CLAIM**

The ornamental design for an unmanned cargo delivery aircraft, as shown and described.

DESCRIPTION

FIG. 1 is a top front perspective view of the unmanned cargo delivery aircraft with the cargo pod.

FIG. 2 is a bottom rear perspective view thereof.

FIG. 3 is a front view thereof.

FIG. 4 is a back view thereof.

FIG. 5 is a left side view thereof.

FIG. 6 is a right side view thereof.

FIG. 7 is a top view thereof.

FIG. 8 is a bottom view thereof.

FIG. 9 is a top front perspective exploded view of the unmanned cargo delivery aircraft with the cargo pod detached.

FIG. 10 is a bottom rear perspective view thereof.

FIG. 11 is a front view thereof.

FIG. 12 is a back view thereof.

FIG. 13 is a left side view thereof.

FIG. 14 is a right side view thereof.

FIG. 15 is a top view thereof; and,

FIG. 16 is a bottom view thereof.

The broken lines shown in the drawings depict portions of the environment that form no part of the claimed design.
